UNITED STATES PATENT OFFICE

WILLIAM ZAK, OF SAN FRANCISCO, CALIFORNIA

DESIGN FOR A VEHICLE NONSKID TIRE

Application filed January 31, 1929. Serial No. 29,858. Term of patent 14 years.

To all whom it may concern:

Be it known that I, WILLIAM ZAK, a citizen of the United States, residing at San Francisco, in the county of San Francisco and State of California, have invented a new, original, and ornamental Design for a Vehicle Nonskid Tire, of which the following is a specification, reference being had to the accompanying drawing, forming part thereof.

Figure 1 is a perspective view of a portion of a tire showing my new design.

Figure 2 is a diagrammatic view in perspective of a motor vehicle tire, a portion thereof being drawn to illustrate applicant's design.

I claim:—

The ornamental design for a vehicle nonskid tire, as shown.

WILLIAM ZAK.
